UNITED STATES PATENT OFFICE

ALBERT KRAUTZBERGER, OF HOLZHAUSEN, NEAR LEIPZIG, GERMANY

SPRAYING OR SQUIRTING PROCESS AND APPARATUS THEREFOR

Application filed January 25, 1930, Serial No. 423,440, and in Germany January 10, 1929.

The present invention relates to a new spraying or squirting process as well as new apparatus suitable therefor. This new invention enables the material used to be sprayed or atomized according to new principles. The words "paint" or "material" are used in the following only as generic names for all solvent, cleansing and binding media which come into consideration in the painting or building arts, which media, under pressure, are squirted or sprayed in continuous or subdivided streams, either as such or against one another, and thereby are subdivided; or else they are sprayed or squirted with the assistance of compressed air, steam, or other suitable compressed gases.

This new process is called the "circulation process" by the inventor. It opens up new fields of employment for the painting and coating appliances operating with or without compressed air. The spraying apparatus necessary herefor are known under the name of "Sprio", wherefor their working is not further explained here. For carrying out the present invention a new kind of construction of the apparatus known under the name of "Sprio", as well as also of the paint conduit, is necessary, which, according to the invention, is fed by pumps or other means, so that the paint is brought into circulation in the most serviceable manner and is supplied to the squirting head. Vessels may serve herefor from which the paint materials are removed by pressure and are supplied to the "Sprio" in the prescribed manner.

The following is attained thereby:

(a) The paint atomizing process known per se, which serves for whitewashing, is improved, if line wash compressed e. g. by piston pressure, is supplied to the paint-squirting nozzles in the most varied devices (squirting tubes, or the like).

(b) Likewise, by the present invention, all spraying and squirting processes are placed on new principles, according to which compressed air serves as atomizing agent (e. g. for lacquers) and in which otherwise, in the already known manner, the material sprays from the paint nozzles, flows or is pressed out

of these, is taken up by the atomizing air and is scattered.

In all these cases the novelty consists in this that sieved paints are either mechanically moved or brought into circulation according to the law of gravity flow. For the former case a paint pump mechanism is provided which is connected in any manner with the material conduits as well as with the spraying head of the "Sprio" apparatus. The paint conduit may be surrounded by flexible pipes which conduct hot compressed air, or the conduit is swept over by hot air, e. g. when working in compartments specially constructed herefor (paint dust collectors). Unnecessary dilution of paints capable of being applied by coating (in order to raise the scattering capability), as well as the unnecessary appearance of mist and paint dust connected therewith, is thereby dispensed with and the squirting and spraying capability is raised owing to the material being continuously kept hot. The deposition of lime washes and distempers cannot occur. The whole "Sprio" plant may be flushed out and cleansed when necessary. By suitable adjustment of a regulator the paint circulation proceeds in front of the latter regulator. The "Sprio" apparatus may thereby be put out of action or may be exchanged by another. Older spraying processes are given completely new fields of application which serve in the painting art, for filling by squirting, for coating surfaces and so forth.

The apparatus serving for carrying out the present invention is shown schematically in two constructional forms, by way of example, in Figures 1-3. Fig. 1 is a side view, partly in section, through the squirting apparatus proper (Sprio); Fig. 2 is a section through another constructional form of the squirting head; Fig. 3 is a side view, in partial section, of a completed plant working on the "circulation process" having two "Sprios", which enable the process according to the present invention to be carried out.

The spraying apparatus ("Sprio") working with or without compressed air is made up of the main parts 1 and 2, viz. the spraying head, and the body member. The latter car-

ries the already known air- and paint-valve controls, which are actuated by the lever 7. The spray head is constructed for carrying out the present process for example as follows:

Referring to Figure 1, 8 is the main tube. This carries the plate 10 furnished with the paint squirting nozzles 9 and having the shoulder 1b and the disc sieve 11. The shoulder 1b carries the air tube 12. This is fed from the air connection 29; it leads the compressed air from the body member 2 to the squirting-head member and supplies the air nozzles 13. For this purpose the plate 10 is provided with annular chambers 14 or the like. The main tube 8 also has a bottom 15. This carries the needle seal, which is not shown, and the idle running threaded bush 57, which serves as a connecting member to the body 2. The bottom 15 also carries a guide member 16 for the paint needle. On the body member 2 there is also a flexible compressed air pipe 5 which, if necessary, surrounds the pipe 3; so that when hot air is supplied to the flexible pipe the said hot air warms the pipe and consequently the paint also. The main tube 8 also has two paint supply tubes 17, 18 which, connected by the regulator 6 (which may also be a multi-way cock) form a loop tube. By suitable adjustment of the regulator 6 the material to be squirted is led either according to Figure 1 in the direction of the arrows *a*, or according to Figure 2 in the direction of the arrow *b*.

According to Figure 2 the paint regulating spindle 19 is guided in the sieve disc 11. Further needles 20 may also be provided on the spindle 19, which needles likewise are guided in the disc sieve 11 and serve for closing up other paint squirting nozzles 9. The latter are constructed according to need and arranged beside the air nozzles 13. For the rest the fitting out of the head member 1 is as shown in Figure 1. The main tube 8 may carry paint containers, which are connected in any way with the tubes 17, 18 (loops) so that the vessels containing the material (in the vertical position) work according to the flowing system, when they are arranged at a suitable height or work under pressure.

In any case, with the described paint conduit 3, 4 (Fig. 3) hot tar, for example, cannot cool down, either in the conduits 17 and 18 or in the regulator 6 or in the "Sprio" itself; also deposition of lime wash is prevented hereby, as well as stoppages in the nozzles. The direction of flow *b* is chosen, for example, when the "Sprio" and its paint conduits, as well as the containers for the material are to be flushed out and thereby cleaned with cleansing agents or solvents, and the flushing liquid is led into open vessels, or into such which are also under pressure, wherefor

these vessels then work under different pressures. The charging and cleansing is the same when the paint circulation is effected by means of a pump mechanism.

In the paint pump mechanism shown in Figure 3 the paint material is supplied to the pump 21 by means of the tube 22 from the paint container 23. The container 23 is provided with a sieve 24, by which the paint flowing back into the container is cleansed. The paint conduit 4 may be provided with elbows 25, from which the flexible paint pipes are fed. The feeding back tube 4 for the paint is provided with a pressure gauge (manometer) 26 and a regulating cock 27. From the latter the paint (circulated by the pump 21) runs through the sieve 24 back into a container 23. Thus the paint, or the flushing liquid is continuously maintained in circulation and cleansed, as well as supplied to the spraying apparatus ("Sprio") for squirting or spraying purposes. The paint circulation tubes are surrounding as required by a flexible compressed air tube, which supplies compressed air to the flexible tube 28 and to the spraying apparatus ("Sprio"); this prevents the heated paint material from solidifying during cold weather and in the course of circulation, whereby the spraying capability of the paints (without addition of diluents) is promoted. The loop tube 3, 4 may be connected at a suitable place, e. g. at 4a, by tubes and reversing cocks, so that then the paint runs in the reversed direction through the conduits and the "Sprio".

Of course the process here described may be carried out not only with the apparatus disclosed in Figs. 1 to 3 as well as in the present description, but all details coming within the scope of the present invention may be varied as desired; this extends to the fitting out of the "Sprio" plant and its construction in all main and subsidiary parts.

What I claim is:

1. A device of the class described comprising a main tube, a spraying head fitted in one end thereof, paint supply tubes connected with said tube, paint conduits communicating with the paint supply tubes, a container for supplying paint to the conduits and said tubes for circulation in the main tube, a pipe surrounding one of the paint conduits adapted to receive heated air, and a regulator between the paint supply tubes and paint conduits for controlling the circulation of paint through the main tube.

2. A device of the class described comprising a spraying head including a main tube, a plate fitted in one end of the tube, said plate having an annular chamber therein, said plate having outlet nozzles communicating with the annular chamber, means for conducting compressed air into the chamber for discharge from the nozzles, a paint feed nozzle in the plate, a sieve in the main tube, a

paint controlling spindle slidable in the sieve and engaged in the feed nozzle, a pair of paint supply tubes communicating with the main tube, means for causing paint to enter the main tube through one supply tube thence through the other supply tube, and means associated with the paint supply tubes for changing the direction of flow of paint through the main tube.

10 In testimony whereof I have signed my name to this specification.

ALBERT KRAUTZBERGER.
